OPHTHALMIC MOUNTING

Gerhard A. Ellestad, Rochester, N. Y., assignor to
 Bausch & Lomb Optical Company, Rochester,
 N. Y., a corporation of New York

Application March 27, 1935, Serial No. 13,308

9 Claims. (Cl. 88—47)

The present invention relates to ophthalmic mountings and more particularly to mountings which are attached to lenses to provide rimless spectacles.

5 One of the objects of the present invention is to provide an improved ophthalmic mounting. Another object is to provide an improved rimless mounting which can be quickly and permanently attached to a lens without the use of screws. A 10 further object is to provide a rimless mounting in which the two straps are separate and independent. A further object is to provide an ophthalmic mounting having independent straps in which the straps are anchored together at both 15 ends by a unitary retaining element. These and other objects and advantages reside in certain novel features of construction, arrangement and combination of parts as will hereinafter be more fully set forth and pointed out in the appended 20 claims.

20 Referring to the drawing:

Fig. 1 is a fragmentary view of a rimless mounting embodying my invention.

Fig. 2 is a horizontal sectional view of same.

25 Fig. 3 is a rear view of the front strap of the mounting.

One embodiment of my invention is illustrated in the drawing wherein 11 indicates a bridge secured to a lens 12 by a mounting indicated 30 generally at 13. The bridge 11 is fixed to the shoe 14 which carries the front strap 15 and the strap 15 is provided with a projection 16 having reentrant grooves 17, which projection extends into an opening 18 adjacent the edge of the lens 35 12. A groove 19 is formed in the strap 15 and extends from the projection 16 toward the edge of the lens. The rear face of the shoe 14 is formed with a recess 20 having an internal depression 21.

40 The rear strap 22 of the mounting 13 is separate from the front strap 15 and has a tapered aperture 23 in alignment with the opening 18. The other end of the rear strap 22 has a projection 24 formed with a reentrant neck portion 45 25. This projection 24 is adapted to extend into the recess 20 of the shoe 14 and a groove 26 is formed in the strap 22 between the aperture 23 and a point adjacent the projection 24.

50 In assembling my improved mounting the front strap 15 is placed on one surface of the lens 11 so that the projection 16 extends into the lens opening 18 and the shoe 14 abuts the edge of the lens 12. The rear strap 22 is then 55 placed on the other surface of the lens with the

projection 24 extending into the recess 20 and the aperture 23 in substantial alignment with the opening 18. While the lens and mounting are so held, a fusible substance 27 is introduced through the aperture 23. Heat is applied so that 55 the substance 27 is rendered fluid or plastic and it is then forced into the opening 18, the grooves 19 and 26 and the recess 20, where it is allowed to harden, thus securing the mounting to the lens. The projections 16 and 24 with their reentrant grooves 17 and 25, respectively, the tapered aperture 23 and the recess 20 with its depression 21 serve as anchoring means to secure the straps in the substance 27 and thus anchor the straps to the lens. The fusible substance 27 may be a 15 low melting point metallic alloy or a non-metallic composition such as the pyroxylin substance sold under the trade name of "Lumarith" for example. By making the mounting of two pieces, it is possible to accommodate lenses of different 20 thickness and the fusible substance 27 extending along the grooves 19 and 26 serves to hold the lens tightly whether the straps 15 and 22 be flat 25 against the surfaces of the lens or not.

From the foregoing it will be apparent that I 25 am able to attain the objects of my invention and provide a new and improved ophthalmic mounting capable of being readily and rapidly secured to lenses of different thicknesses without the use of screws. Various modifications can, of 30 course, be made without departing from the spirit of my invention or the scope of the appended claims.

I claim:

1. An ophthalmic mounting comprising two 35 structurally independent straps positioned, respectively, on opposite surfaces of a lens having an opening adjacent one edge, anchoring means on each strap adjacent said opening, further anchoring means on each strap beyond the edge of 40 said lens, and a fusible retaining element secured to all of said anchoring means.

2. An ophthalmic mounting comprising two 45 structurally independent straps positioned, respectively, on opposite surfaces of a lens having an opening adjacent one edge, anchoring means on each strap adjacent said opening, further anchoring means on each strap beyond the edge of 50 said lens, and a fusible retaining element secured to all of said anchoring means, said retaining element substantially filling said opening.

3. An ophthalmic mounting comprising two 55 independent straps positioned, respectively, on opposite sides of a lens having an opening adjacent one edge, anchoring means on one strap extend-

- ing into said opening, an aperture in the other strap substantially in alignment with said opening, cooperating anchoring means on said straps beyond the edge of said lens, a groove in each strap extending from said opening toward the edge of said lens and a retaining element extending through said aperture into said opening and along said groove and into engagement with each anchoring means.
10. 4. An ophthalmic mounting comprising two independent straps positioned, respectively, on opposite sides of a lens having an opening adjacent one edge, anchoring means on one strap extending into said opening, a tapered aperture on the other strap substantially in alignment with said opening, cooperating anchoring means on said straps beyond the edge of said lens and a retaining element extending through said aperture into said opening and into engagement with each anchoring means.
15. 5. An ophthalmic mounting comprising two independent straps positioned, respectively, on opposite sides of a lens having an opening, a projection adjacent one end of one strap extending into said opening, a recess adjacent the other end of said strap, a projection adjacent one end of said second strap extending into said recess, an aperture in said second strap opposite said opening and a retaining element extending through said aperture into said opening and said recess and surrounding said projections.
20. 6. An ophthalmic mounting comprising two structurally independent straps positioned, respectively, on opposite sides of a lens having an opening, a projection on one of said straps extending into said opening, a reentrant anchoring

groove on said projection, a tapered aperture on the other strap and fusible retaining means extending through said aperture into said opening and engaging said groove and projection and the wall of said opening.

7. An ophthalmic mounting comprising two spaced straps positioned, respectively, on opposite faces of a lens having an opening, anchoring means on one of said straps extending into said opening, the other strap having an aperture and a fusible retaining element positioned in said aperture and opening and anchored to said anchoring means, said element being in engagement with the walls of the opening and aperture.

8. An ophthalmic mounting comprising a strap positioned in contact with the surface of a lens having an opening, anchoring means on said strap extending into said opening and a fusible retaining element positioned in said opening, said element being in contact with the wall of said opening and secured to said anchoring means, said element extending over the other surface of said lens.

9. An ophthalmic mounting comprising two structurally independent straps positioned, respectively, on opposite surfaces of a lens having an opening adjacent its edge, means for securing said straps to each other and to the lens, said means comprising anchoring means on each of said straps adjacent to said opening and further anchoring means on each of said straps adjacent to the edge of the lens, and a fusible retaining means filling said opening and secured to all of said anchoring means.

GERHARD A. ELESTAD.
